UNITED STATES PATENT OFFICE.

WILLIAM CHARLES SPRINGER, OF BELLEVILLE, ONTARIO, CANADA.

LOCK.

Application filed November 28, 1924. Serial No. 752,630.

To all whom it may concern:

Be it known that I, WILLIAM C. SPRINGER, of the city of Belleville, in the county of Hastings, Province of Ontario, Canada, a citizen of the United States of America, have invented certain new and useful Improvements in Locks, of which the following is a specification.

This invention relates to locks provided with a spindle-operated latch and my object is to devise a very simple and inexpensive construction of the latch operating mechanism and, where a dead bolt is employed in the lock, to utilize a single spring for the tumbler of the dead bolt and for the return of the latch operating mechanism to normal position.

I attain my objects by means of the constructions hereinafter described and illustrated in the accompanying drawings in which—

Fig. 1 is a side elevation of a lock constructed in accordance with my invention with the detachable side plate removed; and

Fig. 2 a side elevation of the latch bolt and its operating mechanism looking downward.

In the drawings like numerals of reference indicate corresponding parts in the different figures.

The lock casing, as usual, comprises a stationary plate 1 provided with the integral rim 2 and the face plate 3, the latter being formed with the usual apertures for the passage of the latch bolt 4 and dead bolt 5. The latch bolt is formed with a slot 6 and a recess 7 in its rear end adapted to partly receive the coil spring 8 which bears against the adjacent part of the rim 2. This spring tends to maintain the latch bolt in its normally extended position. 9 is the spindle hub rotatably mounted as usual in the fixed side plate 1 and the removable side plate 10 of the lock casing. The hub is provided with the usual projections 11 for operating the latch. 12 is the latch lever, which is fulcrumed intermediate its ends on the stump 13 and is provided with a pin 14 projecting into the slot 6 of the latch bolt. Normally the pin lies at the rear end of the slot 6 so that the latch bolt is free to recede when the bevelled end of the latch contacts with a keeper when the door to which the lock is connected is closed. The end of the latch lever opposite the pin 14 is engaged by a link 15 which is also engaged by one of the hub projections 11. The latch lever is provided with a third arm 16 with which engages the lower hub projection 11. Thus, when the hub is rotated in one direction, 60 the latch lever is rocked to throw back the latch by the direct engagement of the hub with the latch lever and when the hub is rotated in the opposite direction, the latch lever is rocked through the medium of the 65 link 15.

The link 15 is preferably constructed as follows. The end 17 underlies the upper end of the latch lever 12, which is rabbeted to fit over this end. The other end of the 70 latch lever underlies the adjacent hub projection 11 also rabbeted to overlie this end. Shoulders 18 and 19 are formed on the link for engagement by the latch lever and hub projection respectively. A third shoulder 75 20 is preferably formed on the link, the end of the latch lever lying between the shoulders 18 and 20 so that the link will always follow the movements of the latch lever in either direction. The link also lies between the adjacent part of the rim 2 and the hub 9. With this arrangement no 80 specially constructed guide is necessary for the link. As the latch bolt has a pin and slot engagement with the latch lever, no 85 other guide or support is necessary for the rear end of the latch bolt. The coil spring 8 is made only of sufficient strength to return the latch bolt to its normal position after it has been pushed back by engagement with the keeper as hereinbefore referred to, and it is not desirable that it be made of sufficient strength to also turn the latch lever and spindle hub to their normal positions. For this purpose I provide another spring which serves also the purpose of tending to maintain the tumbler of the dead bolt in its normal position. The dead bolt is formed with a slot 21 through which extends the stump 22 which thus forms 90 a guide for the bolt. On this stump is fulcrumed the tumbler 23 which, as usual, is provided with the projection 24 adapted to lie on either side of the projection 25 on the dead bolt, so that the tumbler serves to 95 lock the dead bolt either in its extended or retracted position. A projection 26 is also formed on the tumbler and a projection 27 on the latch lever. A bent spring 28 engages these projections and the stump 22. This 100 spring thus serves the dual purpose hereinbefore referred to.

105

110

From the above description it will be seen that I have devised a very simple and inexpensive lock, since only two stumps are required and no special guides or other fittings for the parts of the lock.

5 What I claim is:—

1. In a lock the combination of a casing; a latch bolt slideable in the lock casing; a spindle hub journalled in the lock casing, provided with latch lever actuating projections; a latch lever fulcrumed intermediate of its ends; a pivotal connection between one end of the lever and the latch bolt; a sliding link forming an operating connection between the opposite end of said lever and one of the hub projections; and an arm on said lever adapted for engagement by the other hub projection.

2. In a lock the combination of a casing having a front plate apertured for the passage of a latch bolt; a spindle hub journalled in the casing provided with latch lever engaging projections; a latch lever fulcrumed intermediate of its ends; a pivotal connection between one end of the latch lever and the latch bolt, said connection forming the sole support for the rear end of the latch bolt; a sliding link forming an operating connection between the opposite end of said lever and one of the hub projections; and an arm on said lever adapted for engagement by the other hub projection.

3. In a lock the combination of a casing; a latch bolt slideable in the casing; a latch lever fulcrumed intermediate of its ends; a pivotal connection between one end of the latch lever and the latch bolt; a sliding link forming an operative connection between the opposite end of the said lever and one of the hub projections; a flange on the lock casing parallel to said link, said link being guided between the spindle hub and said flange; and an arm on said lever adapted for engagement by the other hub projection.

45 4. In a lock, the combination of a casing, a spindle hub journalled therein provided with latch lever engaging projections; a latch lever fulcrumed in the casing directly

engaged by one of the hub projections; and a sliding link having shoulders engaging respectively the other hub projection and another arm of the latch lever.

5. In a lock the combination of a casing; a spindle hub journalled therein provided with latch lever engaging projections; a latch lever fulcrumed in the casing directly engaged by one of the hub projections; and a sliding link having shoulders spaced inwardly from its ends engaging respectively the other hub projection and another arm of the latch lever, said latch lever and hub projection being rabbeted to overlie the ends of the link.

6. In a lock the combination of a casing; a spindle hub journalled therein provided with latch lever engaging projections; a latch lever fulcrumed in the casing directly engaged by one of the hub projections; a sliding link having shoulders spaced inwardly from its ends engaging respectively the other hub projection and another arm of the latch lever, said latch lever and hub projection being rabbeted to overlie the ends of the link; and a flange on the casing parallel to said link retaining it in position relative to the hub and latch lever.

7. In a lock the combination of a stump; a latch lever fulcrumed on the stump; a dead bolt lock tumbler; a latch bolt positioned between the aforesaid stump and the tumbler and having a pin-and-slot connection with the latch lever; a stump on which said tumbler is fulcrumed; a bent spring engaging the last mentioned stump and having one end engaging the tumbler and the other end extended across the latch bolt and engaged with the latch lever; and a second spring engaging the latch bolt and a stationary part tending to extend the said latch bolt, whereby the latch bolt may move back against spring pressure without moving the latch lever and the first mentioned spring.

Signed at Belleville, this 24th day of October, 1924.

WILLIAM CHARLES SPRINGER.
